UNITED STATES PATENT OFFICE.

JOHANN PETER NOWOTNICK, OF COLOGNE-ON-THE-RHINE, GERMANY.

CLOTHES PEG.

Application filed July 24, 1928, Serial No. 295,043, and in Germany October 27, 1926.

This invention relates to a clothes-peg adapted to be locked so as to protect hat, walking stick, umbrella, overcoat and other clothes against theft.

vice. The front end of the bow *c* is bent upward and has a slight curved end face *i* designed to securely hold a hat to be clamped between the arm *b* and the bow *c*, as shown in Fig. 3.

5 The commonly used devices for this purpose consist generally of a stationary peg or suspending arm over which a bow is placed designed to secure the garments, said bow being adapted to be shifted when it is
10 in the extreme position.

When the device has to be used, the bow ⁵⁰ *c* is raised. The garments to be suspended are hung on the rear end of arm *b*, walking sticks, umbrellas and the like being preferably hooked into chains *k* on the rear portion of the arm *b*. The rim of the hat is placed flatly on the front portion of the arm *b*, as shown in Fig. 3, whereupon the bow ⁵⁵ *c* is lowered and secured in the lowered position by a separate spring, or in any other known manner. The lateral protecting flaps *d*₁, *d*₂ are then lowered and locked in the lowered position with the aid of the locking flaps *e*₁, *e*₂ and the lock *h* so that neither the lateral protecting flaps *d* ⁶⁰ nor the bow can be raised. It is absolutely impossible to remove any garment except after having opened the lock with a special key. Cutting off the suspenders of the garments is also excluded. ⁶⁵

The devices of known type do not fulfil in a perfect manner the purpose for which they are designed as they are either not sufficiently secure or not of good appearance.

I claim:—
A safety clothes-peg, comprising in combination with the wall plate, a peg fixed on said wall plate the front portion of said peg being on a higher plane than the rear portion, a bow hingedly mounted on said wall plate, lateral protecting flaps hingedly fixed the one at the right and the other at the left side of said bow, locking flaps hingedly fixed on the front edge of said protecting flaps, and a lock for securing said locking flaps and thereby also said protecting flaps in the operative position so that cutting off the suspenders of garments on the clothes-peg is effectively prevented. 70 75 80

On the front edges of the protecting flaps 40 d_1 , d_2 closing flaps e_1 , e_2 are arranged which are held together by a lock h . The bow c can be raised and held in this position by the action of a spring or other suitable de-

In testimony whereof I affix my signature.

JOHANN PETER NOWOTNICK.
